ISRAEL FOSTER, OF PHILADELPHIA, PENNSYLVANIA.

Design No. 3,242, dated November 17, 1868.

DESIGN FOR A CARPET-PATTERN.

The Schedule referred to in these Letters Patent and making part of the same.

To all whom it may concern:

Be it known that I, ISRAEL FOSTER, of the city and county of Philadelphia, State of Pennsylvania, have originated a new Design for Carpet-Pattern; and I do hereby declare that the accompanying drawing, and following explanation thereof, form a full, clear, and exact description of the said design.

In the drawing, the complete pattern is shown, the face of the carpet presenting a repetition of what appears in the figure, and the pattern, consisting of squares, A, arranged as shown, each square being ornamented by diagonal rows of dots crossing each other.

Diagonal strips, B, arranged in respect to the squares and ornamented as represented, form further features of the invention, and between these strips are inter-

mediate strips, D, the ornamentation of which is too clearly illustrated in the drawing to need minute description.

Irrespective of the colors employed in carrying out the design,

I claim the design for a carpet-pattern, substantially as described, and represented in and by the accompanying drawing.

In testimony whereof, I have signed my name to this specification, in the presence of two subscribing witnesses.

ISRAEL FOSTER.
